UNITED STATES PATENT OFFICE

2,643,063

RAILROAD JOINT

John A. Ross, Klamath Falls, Oreg.

Application February 2, 1951, Serial No. 209,001

4 Claims. (Cl. 238—151)

1

This invention relates to a novel construction of railroad joint capable of being attached to adjacent ends of railroad rails without the use of any fastenings thereby eliminating the necessity of constant maintenance for tightening the nut and bolt fastenings as are conventionally employed for attaching railroad rails to joints and likewise eliminating the danger of such fastenings being removed by unauthorized persons leaving the rails disconnected so that derailment of rolling stock will result.

More particularly, it is an aim of the present invention to provide a joint formed of sections which are so connected that detachment of the sections is impossible except with the use of special tools and equipment and wherein no exposed fastenings are provided which can be removed by an unauthorized person.

Another object of the invention is to provide a joint which is so constructed that its manner of disassembly is concealed when the joint is assembled and secured to its supporting ties.

A further object of the invention is to provide a joint adapted to receive the adjacent ends of adjacently disposed rails and which will permit the rails to slide a limited distance longitudinally of the joint without being disengaged therefrom so that the rails may expand or contract and may move slightly longitudinally when flexed by the weight of rolling stock thereon and without danger of becoming disconnected from the joint, to thereby afford sufficient flexibility of the rails to prevent breakage of the rails due to the rails being held too rigidly, as now frequently occurs.

Another object of the invention is to provide a joint which can be rigidly secured in place due to the fact that no expansion and contraction of the joint must be compensated for thereby making it impossible for one rail to displace another rail longitudinally of the rails in either direction so that each rail is confined by the joints at each end thereof to a specific space between the adjacent ends of the joints which space is sufficient in length to accommodate the length of the rail and a sufficient additional space of approximately one-half inch to compensate for expansion of the rail.

A further object of the invention is to provide a joint which by confining each rail to a specific space makes it impossible for adjacent rails to be dragged one by another and which frequently results in spaces being created between adjacent ends of adjacent rails considerably longer than one-half inch and which are therefore apt to cause derailments.

2

Various other objects and advantages of the invention will hereinafter become more fully apparent from the following description of the drawings, illustrating a preferred embodiment thereof, and wherein:

Figure 1 is a side elevational view showing the assembled rail joint with adjacent ends of adjacent, aligned rails connected to the ends of the joint;

Figure 2 is a top plan view thereof taken substantially along a plane as indicated by the line 2—2 of Figure 1;

Figure 3 is a bottom plan view of the joint with the fishplate removed taken substantially along a plane as indicated by the line 3—3 of Figure 1;

Figure 4 is a similar view with the fishplate applied taken substantially along a plane as indicated by the line 4—4 of Figure 1;

Figure 5 is a cross sectional view through the joint and rail taken substantially along a plane as indicated by the line 5—5 of Figure 1;

Figure 6 is a longitudinal sectional view taken substantially along a plane as indicated by the line 6—6 of Figure 5;

Figure 7 is a cross sectional view taken substantially along a plane as indicated by the line 7—7 of Figure 6 and showing the rail joint in end elevation;

Figure 8 is a side elevational view of one section of the rail joint;

Figure 9 is a bottom plan view thereof;

Figure 10 is a side elevational view of the other section of the rail joint;

Figure 11 is a bottom plan view thereof;

Figure 12 is a cross sectional view taken substantially along a plane as indicated by the line 12—12 of Figure 10;

Figure 13 is a perspective view of the rail joint section illustrated in Figures 8 and 9;

Figure 14 is a similar view of the rail joint section illustrated in Figures 10 and 11, and

Figure 15 is a perspective view looking toward the bottom of the fishplate employed with and as a part of the rail joint.

Referring more specifically to the drawings, the novel railroad rail joint in its entirety is designated generally 16 and consists of a rail joint section, designated generally 17, a rail joint section, designated generally 18, a fishplate, designated generally 19, and a fastening, designated generally 20.

The rail joint section 17, as best illustrated in Figures 8, 9 and 13, includes a pair of elongated vertically disposed substantially parallel walls 21

having corresponding outwardly and downwardly extending flanges at their bottom edges forming base portions 22. The flanges 22 are connected by an integral bottom portion 23 which is disposed in a plane at a right angle to the planes of the walls 21 and which is provided with a recess 24 formed in the outer end of the section 17, for a purpose which will hereinafter become apparent. One end of a rail head 25 is disposed on the upper edges of the walls 21 and terminates in spaced relationship to the outer ends of said walls and substantially in transverse alignment with the inner end of the notch or recess 24. The opposite end portion of the rail head 25 extends substantially beyond the opposite, inner ends of the walls 21. A web 26 which may be formed integral with or suitably secured to the underside of the rail head 25 is disposed longitudinally thereof and centrally with respect to the opposite longitudinal sides of the rail head 25. One end of the web 26 is disposed between and suitably secured to the walls 21 and the opposite end thereof, which is substantially co-extensive with the last mentioned end of the rail head 25, which extends beyond the inner end of the side walls 21, is provided with a downwardly opening notch 27 and an outwardly opening notch 28. The notch 28 is disposed directly beneath the unsupported end of the rail head 25 and the notch 27 is spaced from the inner ends of the walls 21 and from the terminal of the exposed end of the web 26 to provide a web portion 29, located between the walls 21 and notch 27 and a web portion 30, located between the exposed terminal end of the web 26 and the adjacent end of the notch 27. The walls 21 may be provided with aligned fastening receiving openings 31 between their outer ends and the adjacent end of the rail head 25.

The joint section 18 includes a pair of side walls 32 spaced the same distance apart as the walls 21 but which are substantially longer than said walls 21. The walls 32 are provided with corresponding flanges 33 which extend from end-to-end thereof and which form base portions corresponding in cross section to the base portions 22. The outer edges of the base portions 33 are integrally connected from end-to-end thereof by a plate 34 forming the joint section bottom. The bottom 34 is provided with a recess 35 at the outer end of the joint section 18, corresponding to the recess 24. The opposite end of the bottom 34 is provided with a longitudinally disposed outwardly opening notch 36 which is centrally disposed with respect to the side edges of the bottom 34. An elongated longitudinally disposed slot 37 is formed in the bottom 34 between the notch 36 and recess 35 and in alignment with said notch 36. The notch 36 and slot 37 combine to form a portion 38, disposed therebetween, for a purpose which will hereinafter become apparent. A rail head 39, which is substantially shorter than the rail head 25 is secured in any suitable manner to portions of the upper edges of the walls 32 and longitudinally thereof and has one end disposed substantially intermediate of the ends of said walls 32 and an opposite end which terminates adjacent to but spaced from the outer end of the joint section 18 and substantially in alignment with the inner end of the recess 35.

The fishplate 19 includes a substantially flat plate or bottom portion 40 of a length greater than the length of either of the joint sections and substantially equal to the length of the two

joint sections when assembled. Said bottom portion 40 is provided with integral flanges 41 which extend from end-to-end of its side edges and which project upwardly and inwardly from its upper surface. The side edge portions of the bottom 40 and flanges 41 are provided with longitudinally spaced notches 42 in each side edge thereof so arranged that complementary notches of the two side edges are disposed in transverse alignment. The bottom portion, intermediate of its ends, is provided with a longitudinally disposed keyhole-shaped opening, designated generally 43, including a large end 44 and an elongated restricted end 45 in the form of a slot, one end of which opens into the enlarged portion 44. The underside of the bottom 40 on either side of the slot 45 is provided with ramp surfaces 46 which are inclined from the closed end to the open end of the slot 45 so that the ends of the ramp or cam surfaces 46, disposed adjacent the enlarged opening 44, are positioned near the upper surface of the bottom 40 and the opposite ends of said surfaces 46 merge with the underside of the bottom 40 at the closed end of the slot 45.

The fastening 20 comprises a bolt including a shank 47 having a head 48 at one end thereof and a right angularly extending opposite end or terminal 49.

The adjacent ends 50 and 51 of two longitudinally aligned adjacently disposed railroad rails are shown. The rail end 50 fits into the outer end of the joint section 17, as best illustrated in Figure 6, with the web portion of said rail end disposed between portions of the walls 21, the head of said rail end resting upon the upper edges of the walls 21 and abutting or substantially abutting the adjacent end of the rail head portion 25 and the base of the rail end 50 being disposed in the recess 24 beneath the flanges 22. Thus, the walls 21 prevent lateral movement of the rail end 50 relatively to the joint 16, the base of the rail engages under the flanges 22 to prevent the rail end 50 from being displaced upwardly relatively to the joint and the head of the rail resting upon the upper edges of the walls 21 prevent the rail end 50 from being displaced downwardly relatively to the joint 16. However, the rail end 50 may slide longitudinally of the joint 16 inwardly thereof until its head abuts the adjacent end of the head portion 25. The rail end 51 is similarly disposed with respect to the outer end of the joint section 18 with its web between portions of the walls 32, its head resting thereon and extending toward but normally spaced slightly from the outer end of the head portion 39 and its base disposed in the recess 35 below the flanges 33.

With the rail ends 50 and 51 thus engaged in the remote ends of the joint sections 17 and 18, the exposed end of the web 26 of the joint section 17 is inserted downwardly between the walls 32 of the joint section 18, between the inner end of said section 18 and the adjacent end of the head portion 39. When the joint section 17 is thus moved downwardly until the rail head portions 25 and 39 are disposed in the same plane, the web portion 30 will fit into the slot 37 and the web portion 29 will fit into the notch 36. Likewise, the bottom portion 38 of the joint section 18 will fit into the notch 27 of the web 26, as illustrated in Figure 6, to retain the joint sections against longitudinal movement with respect to one another. As thus assembled, the inner end of the slot 37 is spaced from the ter-

terminal of the web 26. The fishplate 19 is then applied longitudinally of the joint sections 16 and 17 from either end thereof with its bottom 40 engaging under said joint sections and its flanges 41 engaging over the base portions 22 and 33. The fishplate 19 is slid or driven longitudinally of the joint sections until its enlarged opening 44 aligns with the exposed end of the slot 37. After the opening 44 has been aligned with the exposed end of the slot 37 the terminal end 49 of the fastening 20 is inserted upwardly through the openings 43 and slot 37 until the bolt head can be positioned in the enlargement 44. The fishplate 19 is then displaced from right to left of Figure 6 to engage the terminal 49 in the web notch 28 and further movement of the fishplate from right to left will cause the cam surfaces 46 to ride the upper or inner side of the bolt head 48 to draw the bolt 20 downwardly so that its terminal 49 will engage on the upwardly facing shoulder of the notch 28 to thereby retain the joint section 17 against upward displacement relatively to the joint section 18. When fishplate 19 is thus driven from right to left to cause the cam surfaces 46 to ride over the bolt head 48 to displace the bolt 20 downwardly the fastener head 48 will be disposed beneath the cam surfaces 46 and the terminal 49 will be abutting the upwardly facing shoulder of the notch 28 to thus prevent the joint section 17 from being displaced upwardly relatively to the joint section 18 to thereby lock the joint sections in assembled relationship.

Conventional railroad spikes 52 are then driven into ties 53 on which the joint 16 is supported and engage in the notches 42 and against the side edges of the flanges 22 and 33 to hold the fishplate and joint sections against longitudinal movement to thereby anchor the joint 16 against any movement relatively to the ties 53 on which it is supported.

If desired, nut and bolt fastenings 54 may extend through the aligned openings 31 and through elongated slots 55 of the rail end 50 to fasten the rail end 50 to the joint section for a limited sliding movement relatively thereto; however, the fastenings 54 are not necessary and are preferably not employed. The side walls 32 are likewise provided with aligned openings 56 to register with the notch 28 and through which a nut and bolt fastening 57, as seen in Figure 7, may extend to additionally secure the joint sections 16 and 17 together although this is not required and the fastening 57 is likewise preferably omitted.

From the foregoing it will be readily apparent that the rail end 51 may slide a limited distance longitudinally in the outer end of the joint section 18 without being disengaged therefrom to allow for expansion and contraction and to afford sufficient flexibility of the rail to allow a sufficient yielding thereof under the load of rolling stock passing thereover. Similarly, if desired the rail end 50 may slide longitudinally relatively to the joint section 17 a sufficient distance to allow for expansion, contraction and flexibility of the rail and without being disengaged therefrom; however, the opposite end, not shown, of the rail end 50 preferably is movable relatively to an end 18 of another joint 16, not shown. It will thus be apparent that a plurality of longitudinally spaced joints 16 will afford fixed spaces therebetween in which rails connected to adjacent ends of adjacent joints may move sufficiently longitudinally to afford ex-

pansion or contraction of the rails and ample flexibility thereof. However, the adjacent ends of adjacent rails are not fastened together and are capable of individually moving toward and away from one another so that any longitudinal movement of one rail will not produce any pull or push on an adjacent aligned rail.

Various modifications and changes are contemplated and may obviously be resorted to, without departing from the spirit or scope of the invention as hereinafter defined by the appended claims.

I claim as my invention:

1. A railroad joint adapted to be interposed between adjacent ends of aligned rails comprising two rail joint sections having abutting rail head portions terminating in spaced relationship to the remote ends of said sections, said joint sections having recessed outwardly opening remote ends adapted to slidably receive the adjacent ends of two adjacently disposed rails for individual longitudinal sliding movement of the rails relatively to the ends of the rail joint, said rail joint sections having spaced parallel wall portions partially defining said recessed ends between which portions of the webs of the rails are disposed for longitudinal sliding movement, above which portions of the heads of the rails are disposed and supported to retain the rails against downward displacement relatively to the joint and beneath which portions of the bases of the rails are disposed to retain the rails against upward displacement relatively to the joint, one of said rail joint sections having an exposed web provided with a notched bottom edge, said other rail joint section having an opposite inner end recessed to accommodate said web, said last mentioned recess opening upwardly for application of or removal of the web through the top of said other rail joint section, and said last mentioned rail section being provided with a bottom portion provided with a longitudinally extending slot and notch for accommodating portions of the web and for interfitting engagement with the notched bottom portion of said web to retain the rail joint sections against lengthwise sliding movement relatively to one another when assembled with said web interfitting in the recessed bottom of the last mentioned joint section.
2. A rail joint as in claim 1, said rail joint sections having laterally enlarged longitudinally aligned base portions, a fishplate having an upwardly opening channel for receiving and partially overlying said base portions, said fishplate being slidably applied to the base portions longitudinally thereof and having a bottom provided with an opening for registration with an exposed end of the slot of the bottom portion of said last mentioned joint section, a headed fastening insertable upwardly through the fishplate opening and slot having an angularly disposed upper end, said exposed web having a notch opening outwardly of an end thereof to receive the angularly disposed end of said headed fastening, and said fishplate having cam surfaces on its underside adjacent the opening thereof to engage over the head of said fastening to displace the fastening downwardly when the fishplate is displaced in one direction relatively to the joint and headed fastening whereby the web is anchored to the fishplate and thereby secured against upward displacement relatively to the last mentioned joint section.
3. A rail joint as in claim 1, the head portions

of the joint sections being spaced from the remote ends of said joint sections a distance approximately equal to the length of the recesses in said remote ends of the joint sections for accommodating the adjacent ends of the heads of the rails on the joint sections beyond the remote ends of the rail head portions thereof.

4. A rail joint as in claim 1, the head portions of the joint sections being spaced from the remote ends of said joint sections a distance approximately equal to the length of the recesses in said remote ends of the joint sections for accommodating the adjacent ends of the heads of the rails on the joint sections beyond the remote ends of the rail head portions thereof, and said recesses in the remote ends of the joint sections each being of a length to accommodate the sliding movement of the rails in directions longi-

tudinally thereof to compensate for expansion or contraction and normal flexing of the rails without disengagement of the rails from the recessed remote ends of the joint.

JOHN A. ROSS.
